SHIELD FOR PINSETTING MECHANISM ON BOWLING LANE

William Bard, 4700 W. 103rd St.,
Oak Lawn, Ill. 60453

Filed Aug. 16, 1973, Ser. No. 388,759

Term of patent 14 years

Int. Cl. D20—03

U.S. Cl. D34—5 DD

FIG. 1 is a front perspective view of a shield for a pinsetting mechanism on a bowling lane;

FIG. 2 is a front elevational view thereof;

FIG. 3 is a side elevational view, the opposite side being substantially identical; and

FIG. 4 is a top plan view thereof, the side opposite being substantially identical.

The back of the design is planar.

I claim:

The ornamental design for a shield for pinsetting mechanism on bowling lane, as shown and described.
